UNITED STATES PATENT OFFICE.

FRANK VOIGTMANN AND SILAS H. POMEROY, OF CHICAGO, ILLINOIS.

WINDOW.

SPECIFICATION forming part of Letters Patent No. 718,403, dated January 13, 1903.

Application filed July 14, 1902. Serial No. 115,507. (No model.)

To all whom it may concern:

Be it known that we, FRANK VOIGTMANN and SILAS H. POMEROY, residents of Chicago, in the county of Cook and State of Illinois, 5 have invented certain new and useful Improvements in Windows, of which the following is a specification.

This invention relates to improvements in windows, and refers more specifically to an 10 improved weathering-guide for use in fire-proof windows or those wherein the casing and sash-rails are made of sheet metal.

The objects of the invention are to provide 15 a construction in which the weathering-guide serves to most effectually seal the joints between the sash and casing at the sides thereof; to provide in a construction of this character means for adjusting the parts relatively 20 to each other to compensate for inaccuracies of manufacture and changes in adjustment due to any of the numerous causes; to provide a construction which permits the weathering-guides to be withdrawn from their seats, so as to release the sash, without disconnecting 25 the weathering-guides from the sash; to provide a construction which is readily accessible for adjustment or removal of the sash, and in general to provide a simple, reliable, and generally improved construction of the 30 character referred to.

To these ends the invention consists in the 35 matters hereinafter described and more particularly pointed out in the appended claims, and the same will be more readily understood by reference to the accompanying drawings, in which—

Figure 1 is an inside elevation of a window equipped with a preferred embodiment of our invention. Fig. 2 is a fragmentary perspective view looking at the outer edge of one of the side rails or stiles of the sash and showing the manner of securing the weathering-guide thereto. Fig. 3 is a transverse sectional view through the side casing and side stiles 45 of both upper and lower sash, the weathering-guide of the lower sash member being shown as withdrawn or retracted in position to permit the removal of the window.

Referring to said drawings, 1 designates as 50 a whole a window-casing of sheet-metal construction and so formed as to provide in its proximate or inner side faces relatively deep

or narrow grooves 2 and 3, respectively located in position to approximately register with the inner faces of the side stile members 55 4 and 5 of the upper and lower sashes. In other respects the window-casing may be of any suitable or approved construction, that shown herein being of a common construction, provided near its outside edge with a 60 seating-rabbet or inwardly-extending shoulder 1', against which the outer sash member rests.

Describing the construction of the sash-frames 4 and 5, the latter may likewise be of 65 any suitable or approved construction; but in the preferred embodiment shown herein the side stiles 4 and 5 are provided with flat inside faces 7 and 8, respectively, and recessed lateral sides 9 and 9'. The recessed 70 or channel-shaped sides 9 and 9' are preferably formed by folding the metal side inwardly upon itself for a considerable distance to form the channel shape shown and whereby double-thick projections or ribs 10 and 11, 75 10' and 11' are formed, extending substantially in the planes of the outer and inner faces of the stiles.

Upon the inner double-thick rib or projection of each sash-stile, as 11 and 11', is adjustably mounted a flat weathering-guide, as 80 12 and 13, which is of suitable width to afford a firm bearing against the face of the rib of the stile and may be adjusted to project outwardly into the corresponding groove 2 or 3 of 85 the window-casing. Said weathering-guides are preferably made adjustable laterally by providing horizontally-extending or transverse slots 14 in the ribs 11 11', through which slots are extended bolts or securing-screws 90 15, which have their inner ends set in suitable threaded holes in the weathering-guides and are provided at their outer ends with heads 16, which overlie the slots. Preferably the bolts 15 are in the form of screw-bolts, 95 which may be more readily disengaged and loosened by the use of the ordinary screw-driver. The length of the slots 14 is such that the weathering-guides may be retracted or moved inwardly sufficient to completely 100 withdraw them from the respective grooves of the window-casing, thereby releasing the sash, so that the latter may be lifted out of the window-frame.

Inasmuch as the width of the weathering-guide is necessarily less than sufficient to completely cover the slots 14 when said guides are projected, means are provided for closing the inner ends of the said slots when the guides are projected, consisting of escutcheon-like plates or covering-strips, as indicated at 17 and 18, which are connected to move with the securing-bolts 15. In the preferred embodiment shown herein said escutcheon-strips consist simply of strips of sheet metal of a width slightly greater than the width of the slots and length somewhat greater than the length of the slots covered thereby and each provided with aperture at one end to receive the screw-bolt 15, to which it is attached. The end of the escutcheon-strip engaged by the screw-bolt is interposed between the weathering-guide and the inside face of the rib 11 or 11', to which it is applied, and, if preferred, in order to bring the contacting face of the weathering-guide and escutcheon-strip flush with each other the escutcheon-strip may be recessed into the weathering-guide, as shown at 19. The opposite or inner end of each escutcheon-strip is arranged to extend through a guide-aperture, as 20, formed through the side wall of the stiles, and the length of the escutcheon-strip is such that when the weathering-guide is projected to the full extent permissible by the length of the slots 14 the escutcheon-strip will still remain engaged with the guide-aperture 20 and will be thereby maintained in register with the slot.

It will be understood from the foregoing description that the details of construction may be considerably modified without departing from the spirit of the invention, and we do not, therefore, limit ourselves to the construction shown herein except to the extent that such construction is made the subject of specific claims.

We claim as our invention—

1. In combination with a window-casing provided with a weathering-guide groove, a sash provided upon its side stile member with a flange-like rib formed to extend coincident with the inner front plane of the stile, a plate-like weathering-guide, and horizontally-disposed guide connections adjustably uniting said rib and weathering-guide, whereby the latter is adapted to be adjustably projected in a direction perpendicular to the side stile, and forms in effect an extension of the rib engaging said guide-groove of the window-casing.

2. In combination with a window-casing provided with a weathering-guide groove, a sash having upon its side stile member a flange-like rib projecting laterally therefrom, a weather-

ing-guide adjustably secured to said rib, and horizontally-disposed slot-and-bolt connections between said weathering-guide and rib, whereby the weathering-guide is adapted to be projected in extension of the rib, and retracted.

3. In combination with a window-casing provided with a weathering-guide groove, a sheet-metal sash, the side stile members whereof are longitudinally channeled in their lateral edges and provided with double-thick flange-like ribs bounding said channels, a weathering-guide for each side stile member, a plurality of horizontally-disposed slots formed through each of the two inner flange-like ribs, and bolts extending through said slots and seated within the respective weathering-guides, for the purpose set forth.

4. In combination with a window-casing provided with a weathering-guide groove, a sheet-metal sash, the side stile members whereof are longitudinally channeled in their lateral edges and provided with double-thick laterally-projecting ribs bounding said channel, a weathering-guide adjustably secured to one of said ribs within said channel by means of slot-and-bolt connections, and escutcheon-plates operatively connected with the securing-bolts and arranged to close the slots, as and for the purpose set forth.

5. In combination with a window-casing provided with a weathering-guide groove, a sash having upon its side stile member a flange-like rib, a weathering-guide mounted upon the inner side of said rib, means for adjustably securing said weathering-guide and rib together comprising slots formed through the rib and bolts inserted through said slots and engaging the guide, and means for concealing said slots comprising escutcheon-plates operatively connected with the guide to extend beyond the edge thereof and in register with the respective slots so as to close the latter when the weathering-guide is projected.

6. The combination with a window-casing provided with a weathering-guide groove, of a sash having opposite flanges on its side stile, a plate-like weathering-guide held against the inner face of one of the flanges out of contact with the opposite flange, and means for retaining the weathering-guide in different positions of adjustment.
